[57] **CLAIM**

The ornamental design for a mounting adaptor for electrical connector, as shown and described.

DESCRIPTION

FIG. 1 is a perspective view of a mounting adaptor showing my new design.

FIG. 2 is a top plan view thereof on an enlarged scale, the bottom being a mirror image.

FIG. 3 is a right side elevational view thereof on an enlarged scale.

FIG. 4 is a front elevational view thereof on an enlarged scale.

FIG. 5 is a rear elevational view thereof on an enlarged scale.

FIG. 6 is a left side elevational view thereof on an enlarged scale.

FIG. 1

FIG. 2

FIG. 4

FIG. 3

FIG. 5

FIG. 6
